(57) **CLAIM**

I claim the ornamental design for a barbecue, as shown and described.

DESCRIPTION

FIG. 1 is a perspective view of a barbecue, showing my new design with a cover thereof in a closed position and a trigger and a hammer in a forward position;

FIG. 2 is a perspective view thereof, illustrated with the cover in an open position;

FIG. 3 is a left-side elevational view of FIG. 1;

FIG. 4 is a right-side elevational view of FIG. 1;

FIG. 5 is a rear elevational view of FIG. 1;

FIG. 6 is a front elevational view of FIG. 1;

FIG. 7 is a top plan view of FIG. 1;

FIG. 8 is a bottom plan view of FIG. 1;

FIG. 9 is a perspective view thereof, illustrating the trigger and the hammer in a retracted position; and,

FIG. 10 is a left-side elevational view of FIG. 9.
